UNITED STATES PATENT OFFICE

113,407

DESIGN FOR A CHAIR

Harold R. Uber, Lakewood, Ohio, assignor to The Cleveland Welding Company, Cleveland, Ohio, a corporation of Ohio

Application October 24, 1938, Serial No. 80,636

Term of patent 7 years

To all whom it may concern:

Be it known that I, Harold R. Uber, a citizen of the United States and a resident of Lakewood, county of Cuyahoga and State of Ohio, have invented a new, original, and ornamental Design for a Chair, of which the following is a specification, reference being had to the accompanying drawing, forming a part thereof.

In the drawing:

I claim:

The ornamental design for a chair, as shown.

HAROLD R. UBER.
